ACCOUNTANT'S APPARATUS

Rolf Hurup, Minneapolis, Minn.

Application December 26, 1940, Serial No. 371,800
In Sweden October 21, 1938

12 Claims. (Cl. 282—29)

This invention has relation to an apparatus for employment in connection with the posting of accounts, and the general purpose of the invention is to provide an apparatus adapted to be advantageously used by persons engaged in accounting work toward the procurement of accuracy of posted accounts.

An object is to provide an apparatus of the present character which will be of novel and improved construction.

A further object is to provide an apparatus for use in connection with the posting of accounts wherein will be incorporated various improved features and characteristics of construction novel both as individual entities of the apparatus and in combination with each other.

And a further object is to provide an apparatus for employment by persons engaged in accounting work to the purpose of the procurement of accuracy of posted accounts which will be of simple and inexpensive construction and will be constituted as herein illustrated and described.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible so long as within the spirit of the invention and the scope of the claims which follow.

In the accompanying drawings forming a part of this specification,

Fig. 1 is a top plan view of an apparatus including the principles of the invention disclosed as when applied to use;

Fig. 2 is a longitudinal sectional view of the apparatus, taken on line 2—2 in Fig. 1;

Fig. 3 is a transverse sectional view of said apparatus, taken on line 3—3 in Fig. 1;

Fig. 4 is a detail sectional view, taken on line 4—4 in Fig. 1;

Fig. 5 is a detail sectional view, taken on line 5—5 in Fig. 1;

Fig. 6 is a detail sectional view, taken on line 6—6 in Fig. 1;

Fig. 7 is a plan view of an ordinary type of journal sheet, so-called, customarily employed in the posting of accounts;

Fig. 8 is a fragmentary plan view disclosing the journal sheet of Fig. 7 and an account sheet, so-called, also customarily employed in the post-

ing of accounts, applied to said journal sheet in accordance with the teaching of the invention;

Fig. 9 is a view corresponding with the disclosure of Fig. 8, but showing a different account sheet applied to the journal sheet in manner according to the invention;

Fig. 10 is a front plan view, on a reduced scale, of an apparatus of modified construction including features and characteristics of the invention;

Fig. 11 is a rear plan view of the apparatus of Fig. 10;

Fig. 12 is a detail sectional view, taken on line 15 12—12 in Fig. 10; and

Fig. 13 is a detail sectional view, taken on line 13—13 in Fig. 11.

As is well known to accountants and bookkeepers, there are various items of account which are common to an account sheet and a journal sheet, and it is common bookkeeping practice, in the interest of efficiency, to cause account items which are common to an account sheet and a journal sheet to be simultaneously posted upon the account and journal sheets. That is, common account items are posted upon an account sheet while superimposed upon a journal sheet and caused to be duplicated upon the journal sheet, through the medium of carbon paper, or other duplicating material, placed between the account and journal sheets.

An ordinary journal sheet, denoted 15, of type customarily employed in the posting of business account items contains indicia which is more or less standard, including vertical, juxtaposed columns, each represented 16, for providing appropriately headed fields, indicated 17, 18, 19, 20, 21 and 22, upon said journal sheet intended to be utilized for the posting of business account items. In the disclosure as made, each of the fields 17, 19, 20, 21 and 22 is constituted as two vertical, juxtaposed columns 16, one marked "Debit" and the other marked "Credit," and the field 18 is constituted as a single vertical column 16. In the instance of each of the fields 17, 19, 20, 21 and 22, there is a heading over the Debit-Credit entry of the field designating that the field has relation to its own particular type of item of bookkeeping. The headings as shown for the fields 17, 19, 20, 21 and 22 are "Accounts receivable," "Accounts payable," "Cash," "Merchandise" and "Merchandise sales," respectively, and the heading for the field 18 is "Balance control." The Debit-Credit columns for the fields

17, 19, 20, 21 and 22 are commonly termed the "money fields" of the journal sheet.

Ordinary account sheets, each denoted 23, of type customarily employed in the posting of business account items also contain indicia which is more or less standard, including vertical, juxtaposed columns, each represented 24, for providing appropriately headed fields upon the account sheets intended to be utilized for the posting of business account items. More explicitly, each account sheet employed in ordinary bookkeeping practice includes, among other indicia, an appropriately headed field, indicated 25, for the reception of items of account which are the same as are required to be posted at one or the other of fields such as 17, 19, 20, 21 and 22 upon a journal sheet, and an appropriately headed field, indicated 26, for the reception of items of account which are the same as are required to be posted at a field such as 18 upon said journal sheet. Each field 25 is constituted as two vertical, juxtaposed columns 24, one marked "Debit" and the other marked "Credit," and each field 26 is constituted as a single vertical column 24.

It is to be understood that the journal sheet 15 can include fields such as 17, 19, 20, 21 and 22 additional to or other than those illustrated and hereinbefore enumerated, and that the account sheets employed will be of as many different types as there are different fields such as 17, 19, 20, 21 and 22 to be utilized upon the journal sheet. That is, supposing account items for duplication upon a journal sheet to be those as disclosed in Fig. 7, five different types of account sheets 23 will be employed, as follows:—one type including fields 25 and 26 corresponding to and having designations the same as the fields 17 and 18, respectively; a second type including fields 25 and 26 corresponding to and having designations the same as the fields 19 and 18, respectively; a third type including fields 25 and 26 corresponding to and having designations the same as the fields 20 and 18, respectively; a fourth type including fields 25 and 26 corresponding to and having designations the same as the fields 21 and 18, respectively; and a fifth type including fields 25 and 26 corresponding to and having designations the same as the fields 22 and 18, respectively.

All of the fields 17, 19, 20, 21 and 22 upon the journal sheet 15 are of equal width, and the field 25 upon each account sheet 23 will have the same width as each of said fields 17, 19, 20, 21 and 22. Likewise, the field 26 upon each account sheet will have width equal to that of the field 18 upon the journal sheet. Desirably, all of the fields of both the journal sheet and the account sheet are provided with equally spaced markings or indicating lines for the entry of account items.

The invention presents a novel and improved apparatus for use in connection with the blind posting of account items upon a journal sheet by duplication of account items as posted upon an account sheet designed and constructed with the end in view that said account items will be accurately posted upon said journal sheet, and the apparatus incorporates several novel and improved features and characteristics designed and constructed with the additional end in view that the blind posting of an account item upon a journal sheet at an erroneous field or location thereof can be readily and easily detected. Stated differently, the invention and apparatus herein have relation generally to the matter of accomplishing accurate posting of account items upon a journal sheet by duplication of account items

posted upon an account sheet, and said invention and apparatus also have relation to the matter of posting account items upon a journal sheet so that there can be ready and easy discovery of any 5 "money field" account items which might possibly become inadvertently posted at improper fields or locations upon the journal sheet.

A panel board 27 of rectilinear configuration includes a flat front surface of length and width 10 to nicely receive a journal sheet 15 which is to be posted disposed flatwise upon the panel board. Desirably, the panel board will include supporting elements 28 adjacent the upper edge of its back side so that the panel board when rested upon a 15 desk or other supporting surface will be tilted toward a user.

Clips 29, 29 adjacent two of the corners of the front surface of the panel board 27 are for releasably retaining an end portion, the right end 20 portion as shown, of a journal sheet spread across said panel board, and a clamp arm 30 is for releasably retaining the end portion, the left end portion as shown, of the journal sheet opposite the clips 29, 29 against the panel board.

25 A cylindrical retaining and guide rod 31, disposed longitudinally of the panel board and situated in slightly spaced relation to its upper edge, is mounted at its opposite ends in spaced apart bearings 32, 32 rigid with the upper opposite corners of said panel board. As disclosed, the retaining and guide rod 31 is situated at elevation below the flat front surface of the panel board, out of the way, to offer no interference with the operations of a user of the apparatus.

35 The upper end 33 of the clamp arm 30 is rotatably mounted upon and fixed against longitudinal movement along the retaining and guide rod 31, and the lower end portion 34 of said clamp arm suitably and conveniently supports a 40 latch element 35 adapted to be releasably engaged with a keeper element 36 suitably and conveniently mounted upon the panel board 27 at location adjacent its upper edge. The keeper element 36 is constituted as a flexible wire fixed

45 to the panel board, and a release element 37 slidably mounted in the latch element 35 includes a rounded head 38 of the release element adapted to be depressed against said keeper element 36 to actuate the keeper element to the released position of the latch element. The latch and keeper elements are caused to be assembled together while the release element is in elevated position merely by causing said latch element to be inserted into an opening 39 in the panel board surrounding said keeper element so that a portion of said latch element snaps past said keeper element and the keeper element situates itself in front of said portion, and when the latch and keeper elements are assembled, the clamp arm 30 is engaged against the journal sheet

50 at the time upon said panel board. When said clamp arm is to be swung upwardly upon its axis, as when a journal sheet is to be placed upon or removed from the panel board, the release element is held depressed against the action of the coil spring normally urging said release element upwardly until the latch element has been moved outwardly to position clear of said keeper element, as will be understood.

55 A gripping entity 40 of the apparatus is for releasably securing an end portion, more explicitly, the left end portion, of any one of the account sheets 23 upon the panel board so that the secured account sheet can be disposed flatwise upon a journal sheet retained upon said

60 65 70 75 A gripping entity 40 of the apparatus is for releasably securing an end portion, more explicitly, the left end portion, of any one of the account sheets 23 upon the panel board so that the secured account sheet can be disposed flatwise upon a journal sheet retained upon said

panel board. The gripping entity 40 is also adapted to fasten an edge portion of a sheet of carbon paper 41, or equivalent, placed between the account and journal sheets for duplicating purposes.

Said gripping entity 40 includes an elongated body 42 therecf disposed laterally of the panel board and integrally supported at its upper end by a tubular element 43 slidably and rotatably mounted upon the cylindrical retaining and guide rod 31. Said retaining and guide rod includes spaced apart, longitudinally alined groove seats 44 at its front side, and the tubular element 43 suitably and conveniently supports a spring pressed ball 45 adapted to be resiliently urged into any one of the groove seats 44. The construction and arrangement are such that the resiliently urged ball 45 will be alined with the groove seats 44 when the gripping entity 40 is in contiguous relation with the panel board 27 and will be out of alinement with said groove seats when said gripping entity is swung upwardly about the retaining and guide rod 31 as an axis. The lower edge portion of the front surface of the panel board 27 is provided with spaced apart, longitudinally alined slots 46, including a slot 46 in alinement laterally of said panel board with each of said groove seats 44, and the elongated body 42 of the gripping entity 40 integrally carries a locking lug 47 adapted selectively to lie in the slots 46 when said gripping entity is contiguous with the panel board. The gripping entity 40 is adapted to be adjusted longitudinally of the panel board, thus to adjust an account sheet secured in said gripping entity relatively to a journal sheet retained upon said panel board, by slideable movement of the tubular element 43 along the cylindrical retaining and guide rod 31, and the groove seats together with the slots 46 in lateral alinement therewith provide different stop positions upon the panel board for the gripping entity adapted to situate account sheets at appropriate, proper locations for the simultaneous posting of account items upon the account and journal sheets. When said gripping entity 40 is at any one of its stop positions and against the panel board, with the resiliently urged ball 45 and the locking lug 47 in the corresponding groove seat 44 and slot 46, respectively, the gripping entity is positively located upon said panel board. In order to adjust said gripping entity from one of its stop positions to any other of its stop positions, the elongated body 42 is first swung upwardly about its axis to cause the resiliently urged ball 45 to be moved from the groove seat 44 at the time engaged by said ball and to position out of alinement with the several longitudinally alined groove seats, is then slid longitudinally of the retaining and guide rod 31 to alined relation with the laterally alined groove seat and slot providing the stop position to which it is intended to adjust said gripping entity, and is finally swung downwardly to position against the panel board. Upon downward swinging of said elongated body when in proper alinement with laterally alined groove seat and slot at a stop position, the resiliently urged ball 45 and the locking lug 47 will evidently enter said groove seat and slot, respectively.

The elongated body 42 of the gripping entity integrally includes a thin, elongated gripping strip 48 disposed at a side, the right side as shown, and adjacent the rear of said elongated body, and an elongated gripping piece 49, pivotal-

ly supported, as at 50, upon the elongated body for swinging movement toward and away from the elongated gripping strip 48, is normally resiliently urged against said elongated gripping strip by means of spaced apart coil springs 51 each having one of its ends engaged against said elongated body and its opposite end engaged against said gripping piece. The gripping piece 49 and the gripping strip 48 constitute complementary means of the gripping entity for releasably retaining the different account sheets upon the panel board, and a longitudinally extending shoulder 52 of the elongated body 42 at the inner side or edge of said gripping strip constitutes locating and alining means for the account sheets against which the extreme edge, the left edge as shown, of each account sheet placed in the apparatus is adapted to be engaged. A finger piece 53 secured upon the gripping piece 49 at the side thereof opposite the side of said gripping piece adjacent the gripping strip 48 is for easy accomplishment of separation of said gripping piece and gripping strip, against the resilient action of the coil springs 51, as when an account sheet is to be assembled with or disassembled from the gripping entity.

The elongated gripping piece 49 is provided with index lines 54 having correspondence to the horizontal markings or lines upon the account sheets, and said index lines 54 are suitably numbered, as at 55. Also, a pointer 56 slidably mounted upon the elongated gripping piece 49 is adapted successively to be moved one number at a time to each of the various numbers indicated 35 55. More explicitly, the pointer 56 is adapted to be adjusted one number downwardly along said gripping piece 49 with completion of blind postings upon each line of the journal sheet by duplication of postings upon the account sheet, thus to 40 give visible indication of the next line upon said journal sheet which is to be blind posted. Of course, each account sheet is assembled with the gripping piece 49 at location longitudinally thereof situating the line or lines of the account sheet to be posted over or alined with the line or lines of the journal sheet intended to be blind posted. The pointer 56 is held to the gripping piece 49 by a shank 57 in a hole through said pointer and slidably disposed in a longitudinal slot 58 in said gripping piece, a cross piece 59 upon said shank 57 at the under side of the gripping piece, a button 60 on the shank at the outer side of the pointer, and a small coil spring 61 upon said shank and seated under compression 55 between said button and said pointer. The button 60 constitutes a finger piece for easy manipulation of the pointer.

The panel board 27 is provided with spaced markers, represented 62, 63, 64, 65 and 66, and the elongated body 42 of the gripping entity 40 rigidly supports an indicator 67 having reference to said spaced markers 62, 63, 64, 65 and 66. Also, said panel board is provided with transversely alined sets of markers, denoted 68, 69 and 69, 69 65 and 70, 70 and 71, 71 and 72, 72, respectively, upon the upper and lower portions of the panel board, with which sets, respectively, the fields 11, 19, 20, 21 and 22 of a journal sheet are adapted to be alined. The different stop positions upon 70 the panel board for the gripping entity 40, each provided by laterally alined gripping seat and slot, are numbered 73, 74, 75, 76 and 77 in Fig. 1 of the drawings. When said gripping entity is at stop position 73 the indicator 67 will be at the marker 62 and an account item to be posted

upon an account sheet and duplicated upon the journal sheet 15 at the field 17 will be aligned with the set of markers 68, 68. When the gripping entity is at stop position 74 the indicator will be at the marker 63 and an account sheet item to be duplicated at the field 19 will be aligned with the set of markers 69, 69. When the gripping entity is at stop position 75 the indicator will be at the marker 64 and an account sheet item to be duplicated at the field 20 will be aligned with the set of markers 70, 70. When the gripping entity is at stop position 76 the indicator will be at the marker 65 and an account sheet item to be duplicated at the field 21 will be aligned with the set of markers 71, 71. And when the gripping entity is at stop position 77 the indicator will be at the marker 66 and an account sheet item to be duplicated at the field 22 will be aligned with the set of markers 72, 72. For the purpose of easy differentiation among the several markers, these may be distinctively different. As shown, the markers 62, 68, 68 are red, the markers 63, 69, 69 are blue, the markers 64, 70, 70 are purple, the markers 65, 71, 71 are green, and the markers 66, 72, 72 are orange.

As will be apparent from Fig. 7 of the drawings, all account items to be posted at the field 18, headed "Balance control," upon the journal sheet 15 are in a single column, and the construction and arrangement are such that account items for said field 18 can be posted upon each of the different account sheets, at the field 26, headed "Balance," and duplicated upon the journal sheet while the gripping entity 40 is situated at the first stop position 73 at the left, each field 26 being placed at the same distance from the left end of the account sheet having the field and so as to be properly aligned with the field 18 when the gripping entity 40 is at said first stop position 73. Also, additional account items, not necessary to be mentioned, can be posted upon each different type of account sheet and duplicated upon the journal sheet 15 while said gripping entity is at said first stop position.

Within the disclosure of the invention, the fields 25 of the different account sheets could be situated upon said account sheets so as to be at equal distance from the left ends of the account sheets. That is, the field 25 upon an account sheet for receiving account items to be duplicated at the field 17 upon a journal sheet could be, for example, at the same distance from the left end of the account sheet as is the field 25 upon a different account sheet for receiving account items to be duplicated at the field 19, or at any of the other "money fields," upon a journal sheet. In such an event, the stop positions 74, 75, 76 and 77 would be at equal distance apart, and said stop position 74 would be at this same distance from the initial stop position 73 plus a measurement representing the width of the field 18, situated upon the journal sheet 15 between the fields 17 and 19 in the disclosure as made. However, were the fields 25 having reference to the different "money fields," 17, 19, 20, 21 and 22, upon a journal sheet spaced equidistantly from the left ends of the account sheets there would obviously be opportunity for inadvertent incorrect posting extremely hard to later discover of "money field" account items of an account sheet upon a journal sheet. That is, "money field" account items which should be posted, properly, at specific ones of said fields 17, 19, 20, 21 and 22 could possibly become posted at wrong "money fields" upon a journal sheet in vertical alignment with the jour-

nal sheet "money fields" where erroneously included and thus not easily discoverable.

While a "money field" such as 25 upon an ordinary account sheet is required to be within a limited range along the length of the account sheet, such range is of greater magnitude than is required for the width of any of the money fields 17, 19, 20, 21, 22 and 25, which are, as disclosed, of the same width. To the end that "money field" account items posted upon a field 25 of an account sheet and duplicated blind upon a journal sheet 15 will be aligned with, and only with, the particular "money field," 17, 19, 20, 21 or 22, upon said journal sheet intended to receive 15 said "money field" account items, the field 25 upon each of the different types of account sheets employed is placed at a different distance, within the range permissible, from the left end of the account sheet than is the "money field" upon any 20 of the other types of account sheets, and the stop positions 73, 74, 75, 76 and 77 are situated upon the panel board 27 to cause the field 25 of each different type of account sheet to be aligned with its proper field upon the journal sheet when the 25 gripping entity 40 while holding the account sheet is at the corresponding and proper stop position. Stated differently, the fields 25 having relation to the different fields 17, 19, 20, 21 and 22, respectively, are each at variable distances from the 30 left ends of the account sheets, and the stop positions are spaced to make possible the selective alignment of fields 25, 17 and 25, 19 and 25, 20 and 25, 21 and 25, 22, respectively. Evidently, in order to obtain alignment of a "money field" 35 25 upon an account sheet 23 at a certain distance from the left end of the account sheet with a corresponding "money field" upon a journal sheet, the corresponding stop position upon the panel board will be situated substantially at this 40 same distance to the left of said corresponding journal sheet "money field." Therefore, for proper posting of any "money field" account item of the field 25 shifted or adjusted toward the left within the permissible range upon an account sheet there must be an off-set shifting or adjusting 45 of the corresponding stop position upon the panel board toward the right, and vice versa.

The construction and arrangement as illustrated and described, while not precluding the 50 possibility of the duplication of "money field" account items posted upon an account sheet at erroneous "money field" locations upon a journal sheet, obviously preclude the possibility that any "money field" account item posted upon an account sheet and duplicated upon a journal sheet can be vertically aligned with account items in any of the journal sheet "money fields" where erroneously included, thus to be difficult of discovery. Instead, the apparatus includes provision 55 whereby an account item, more specifically, a "money field" account item, erroneously posted blind upon a journal sheet by duplication of a posting as made upon an account sheet will be of necessity out of vertical alignment with the 60 "money field" in which erroneously placed, and thus situated where it can be readily and easily detected.

The apparatus disclosed in Figs. 10 to 13 may be substantially similar in most respects to the apparatus as hereinbefore described. An essential difference between the disclosures of Figs. 1 to 6 and Figs. 10 to 13, however, is that whereas the gripping entity 40 of the former is adapted to be manually moved to each of the different stop 75 positions 73, 74, 75, 76 and 77, the gripping entity

of the latter is adapted to be mechanically moved from its normal location at the initial stop position 78, corresponding to the stop position 73, to each of its stop positions 79, 80, 81 and 82, corresponding to the stop positions 74, 75, 76 and 77, respectively, and manually moved back toward and to said initial stop position 78.

A wound spring 83 suitably and conveniently mounted upon the panel board at its back side includes an end portion secured, as at 84, to the tubular element 43. Said wound spring 83 has potential capable of moving said tubular element 43 and the gripping entity 40 supported thereby a considerable distance toward the right end of the panel board, and a stop element 85 fixed to said tubular element 43 is adapted to selectively engage against stop shoulders 86, 87, 88, 89 and 90, corresponding to the stop positions 78, 79, 80, 81 and 82, respectively, of a lever 91 having one of its ends pivoted, as at 92, upon said panel board. All of the stop shoulders face toward the left of the panel board, and the wound spring is situated at the right. A tension coil spring 93, having one of its ends attached, as at 94, to an element fixed upon the panel board and its other end attached, as at 95, to the end portion of the lever 91 opposite its pivotal support, resiliently urges said lever 91 toward said stop element 85. A link 96 has one of its ends pivoted, as at 97, to the free end of the lever 91, and the end portion of said link 96 opposite said lever 91 includes a longitudinally extending slot 98. A pin or small shaft 99 suitably and conveniently supported upon the panel board rotatably supports an intermediate portion 100 of a compound lever including a single rearwardly extending arm 101 thereof having its rear or outer end pivoted, as at 102, in the longitudinal slot 98. Said compound lever also includes four L-arms which are rigid with each other and with the rearwardly extending arm 101. Each of the L-arms of said compound lever includes a vertical portion 103 and a horizontal portion 104 between the vertical portion and the small shaft 99. The vertical portions 103 are slidably disposed in openings through the panel board and are situated partially in front of and partially in back of said panel board, and the upper end of each vertical portion includes a manipulating key 105 upon its upper end at the front of and spaced from the panel board. Each vertical portion 103 of the compound lever is connected to the intermediate portion 100 by a horizontal portion 104 of said compound lever having length unequal to that of any of the other horizontal portions, the shortest connection between a vertical portion and said intermediate portion having substantially one-quarter the length of the longest connection, the next to shortest connection having substantially one-half the length of said longest connection, and the next to longest connection having substantially three-quarters the length of the longest connection. Small tension springs 106 are for normally retaining the manipulating keys 105 at their elevated positions. Evidently, depression through an arc of certain magnitude of the manipulating key closest to the pin or small shaft 99 will cause the lever 91 to be swung through an arc in direction away from the stop element 85 greater than will be the case upon depression of the next adjacent manipulating key through the same arc, and the statement just made is also true with respect to each of the manipulating keys, except the outermost one, and the manipulating keys

disposed further outwardly. The lever 91 will be normally positioned so that the stop shoulder 86 is aligned with the stop element 85, and, as is disclosed, there is a manipulating key 105 corresponding to each of the stop shoulders 87, 88, 89 and 90, respectively.

The construction and arrangement will be such that upon depression of any one of the manipulating keys to thus cause the stop shoulder 86 to be withdrawn from the stop element 85, the lever 91 will be swung in direction away from said stop element a distance to cause the stop shoulder corresponding to the manipulating key which was depressed to be aligned with the stop element.

10 The wound spring 83 of course will cause the tubular element 43 and the gripping entity 40, rigid with said tubular element, to be moved toward the right until the stop element engages and is arrested by the stop shoulder with which 15 aligned. After actuation of the lever 91 the manipulating key which was depressed to cause the actuation will return to its normal position when released. The gripping entity 40 is adapted to be manually moved back toward and to its position 20 where the stop shoulder 86 is engaged with the stop element 85. Clearly, upon manual movement of the gripping entity back to the stop position 73, or back to any of the other stop positions, the corresponding stop shoulder will 25 become situated between the stop element 85 and the wound spring 83 in position to be engaged against by the side of said stop element which is in facing relation to said wound spring.

What is claimed is:

35 1. An apparatus of the character described, comprising a panel board having a front surface adapted to receive a journal sheet for the posting of business account items spread out upon the panel board, means for releasably securing said journal sheet upon said panel board, a gripping entity adapted to support an account sheet for the posting of business account items in superimposed relation to said journal sheet while spread out upon said panel board, means for releasably securing an edge portion of said account 40 sheet at said gripping entity, a guide rod upon said panel board and disposed longitudinally of said journal sheet, a tubular element rigid with said gripping entity and slidably mounted upon said guide rod, and spaced apart complementary means assembled with said panel board and said tubular element, respectively, for releasably securing the gripping entity in fixed relation to the panel board selectively at different locations lengthwise of said journal sheet.

55 2. An apparatus of the character described, comprising a panel board having a front surface adapted to receive a journal sheet for the posting of business account items spread out upon the 60 panel board, a gripping entity adapted to support an account sheet for the posting of business account items in superimposed relation to said journal sheet while spread out upon said panel board, a guide rod upon said panel board and disposed longitudinally of said journal sheet, a tubular element rigid with said gripping entity and slidably mounted upon said guide rod, spaced apart complementary means supported by said panel board and said tubular entity, respectively, for releasably securing the gripping entity in fixed 65 relation to the panel board at each of different predetermined stop positions upon said panel board, means including a clip at one side of the panel board and a clamp arm at the opposite side of said panel board pivotally support- 70 75

ed upon said guide rod for releasably securing said journal sheet upon the panel board, and means for releasably supporting an edge portion of said account sheet to said gripping entity.

3. An apparatus of the character described, comprising a panel board having a front surface adapted to receive a journal sheet for the posting of business account items spread out upon the panel board, a gripping entity adapted to support an account sheet for the posting of business account items in superimposed relation to said journal sheet while spread out upon said panel board, a guide rod upon said panel board and disposed longitudinally of said journal sheet, a tubular element rigid with said gripping entity and rotatably and slidably mounted upon said guide rod, spaced apart complemental means assembled with said panel board and said tubular entity, respectively, for releasably securing the gripping entity in fixed relation to the panel board at each of different predetermined stop positions upon said panel board, means including a clip at one side of the panel board and a clamp arm at the opposite side of said panel board pivotally supported upon said guide rod for releasably securing said journal sheet upon the panel board, and means for releasably supporting an edge portion of said account sheet at said gripping entity.

4. An apparatus of the character described, comprising a panel board having a front surface adapted to receive a journal sheet for the posting of business account items spread out upon the panel board, a gripping entity adapted to support an account sheet for the posting of business account items in superimposed relation to said journal sheet while spread out upon said panel board, a guide rod upon said panel board and disposed longitudinally of said journal sheet, a tubular element rigid with said gripping entity and rotatably and slidably mounted upon said guide rod, and spaced apart complemental means assembled with said panel board and said tubular entity, respectively, for releasably securing the gripping entity in fixed relation to the panel board at each of different predetermined stop positions upon said panel board, said gripping entity being adapted to have swinging movement between a position contiguous with said panel board and a position spaced from the panel board, and said complemental means supported by said panel board being adapted to be in alignment with said complemental means supported by said tubular entity longitudinally of said guide rod when said gripping entity is contiguous with said panel board and the complemental means supported by the panel board being adapted to be out of alignment with the complemental means supported by the tubular entity when the gripping entity is swung to position in spaced relation to said panel board.

5. In a device of the character described, comprising a panel board having a front surface adapted to receive a journal sheet for the posting of business account items spread out upon the panel board, a gripping entity adapted to support an account sheet for the posting of business account items in superimposed relation to said journal sheet while spread out upon said panel board, devices for mounting said gripping entity upon said panel board for slidable movement relatively to said journal sheet, means having potential to cause said gripping entity to be moved longitudinally of said journal sheet, and complemental stop elements assembled with said panel

board and said gripping entity, respectively, for releasably securing the gripping entity in fixed relation to the panel board against tendency of said means to cause said gripping entity to be moved longitudinally of the journal sheet.

6. An apparatus of the character described, comprising a panel board having a front surface adapted to receive a journal sheet for the posting of business account items spread out upon the panel board, a gripping entity adapted to support an account sheet for the posting of business account items in superimposed relation to said journal sheet while spread out upon said panel board, devices for mounting said gripping entity upon said panel board for slidable movement relatively to said journal sheet, means having potential to cause said gripping entity to be moved longitudinally of said journal sheet, spaced apart stop positions upon said panel board, and complemental stop elements assembled with said panel board and said gripping entity, respectively, for releasably securing the gripping entity in fixed relation to the panel board selectively at each of said stop positions against tendency of said means to cause said gripping entity to be moved longitudinally of the journal sheet.

7. An apparatus of the character described, comprising a panel board having a front surface adapted to receive a journal sheet for the posting of business account items spread out upon the panel board, a gripping entity adapted to support an account sheet for the posting of business account items in superimposed relation to said journal sheet while spread out upon said panel board, devices mounting said gripping entity upon said panel board for slidable movement relatively to said journal sheet, means having potential to cause said gripping entity to be moved longitudinally of said journal sheet, spaced apart stop positions upon said panel board, complemental stop elements assembled with said panel board and said gripping entity, respectively, for securing the gripping entity in fixed relation to the panel board selectively at each of said stop positions against tendency of said means to cause said gripping entity to be moved longitudinally of said journal sheet, and manually actuatable mechanism for actuating the complemental stop elements to cause said gripping entity to be released for movement by said means away from one of the stop positions and to position said complemental stop elements relatively to each other to cause the movement of said gripping entity to be arrested at another of said stop positions.

8. An apparatus of the character described, comprising a panel board having a front surface adapted to receive a journal sheet for the posting of business account items spread out upon the panel board, a gripping entity adapted to support an account sheet for the posting of business account items in superimposed relation to said journal sheet while spread out upon said panel board, a guide rod upon said panel board and disposed longitudinally of said journal sheet, a tubular element rigid with said gripping entity and slidably mounted upon said guide rod, spaced apart complemental means supported by said panel board and said tubular entity, respectively, for releasably securing the gripping entity in fixed relation to the panel board at each of different predetermined stop positions upon said panel board, means for releasably securing said journal sheet upon the panel board, and means

for releasably supporting an edge portion of said account sheet to said gripping entity.

9. An apparatus of the character described, comprising a panel board having a front surface adapted to receive a journal sheet for the posting of business account items spread out upon the panel board, a gripping entity adapted to support an account sheet for the posting of business account items in superimposed relation to said journal sheet while spread out upon said panel board, a guide rod upon said panel board and disposed longitudinally of said journal sheet, a tubular entity rigid with said gripping entity and slidably associated with said guide rod, and spaced apart complementary means assembled with said panel board and said tubular entity, respectively, for releasably securing the gripping entity in fixed relation to the panel board at each of different predetermined stop positions upon said panel board.

10. An apparatus of the character described, comprising a panel board having a front surface adapted to receive a journal sheet for the posting of business account items spread out upon the panel board, a gripping entity adapted to support an account sheet for the posting of business account items in superimposed relation to said journal sheet, devices for mounting said gripping entity upon said panel board for movement longitudinally of said journal sheet, and means for causing said gripping entity to be moved step by step longitudinally of said journal sheet.

11. An apparatus of the character described, comprising a panel board having a front surface adapted to receive a journal sheet for the posting of business account items spread out upon the

panel board, a gripping entity adapted to support an account sheet for the posting of business account items in superimposed relation to said journal sheet, devices for mounting said gripping entity upon said panel board for movement longitudinally of said journal sheet, and means for causing said gripping entity to be moved a predetermined distance relatively to said journal sheet.

10 12. An apparatus of the character described, comprising a panel board having a front surface adapted to receive a journal sheet spread out upon said panel board, said journal sheet having fields thereof disposed in juxtaposed columns 15 each for the posting of business account items and including a plurality of different money fields upon said journal sheet, a gripping entity adapted to selectively support, one at a time, different account sheets for the posting of business account items in superimposed relation to said journal sheet while spread out upon said journal sheet. said different account sheets including an account sheet with money field corresponding to each of the money fields upon said 25 journal sheet and the money fields upon each of the different account sheets being situated at position longitudinally of the account sheet different from the money fields upon all others of said different account sheets, devices for accomplishing movement of said gripping entity longitudinally of said journal sheet, and means for causing the money field upon each account sheet to be aligned with the money field upon said journal sheet to which said money field of the account sheet has reference.

ROLF HURUP.
